GOLFER'S ACCESSORY HOLDER OR THE LIKE

William R. Langevin, St. Paul, Minn.

Application October 8, 1958, Serial No. 52,909

Term of patent 14 years

(Cl. D34—5)

FIG. 1

The portions shown in broken lines are for illustrative purposes only.

I claim:

The ornamental design for a golfer's accessory holder or the like, as shown and described.
